CLAIM

The ornamental design for a sanitary article, as shown and described.

DESCRIPTION

FIG. 1 is a top plan view of a sanitary article showing our new design.

FIG. 2 is a bottom plan view thereof.

FIG. 3 is a front elevational view thereof.

FIG. 4 is a rear elevational view thereof.

FIG. 5 is a left side elevational view thereof, and,

FIG. 6 is a right side elevational view thereof.

The bottom of the sanitary article as shown in FIG. 2 has no depth. The lines in grey tones indicate surface indicia.
